C. J. YOUNG.
CLAM SHELL BUCKET.
APPLICATION FILED SEPT. 18, 1911.

Patented Sept. 3, 1912.

2 SHEETS—SHEET 1.

A technical line drawing of a boat's hull and rigging. The hull is a single piece with a flat bottom. The rigging consists of a mast (19) at the top, a boom (17) extending from the side, and various stays and shrouds. Numbered callouts point to specific parts: 1, 2, 3, 4, 5, 6, 7, 8, 9, 10, 11, 12, 13, 14, 15, 16, 17, 18, and 19. The drawing is signed 'Henry' in the bottom left corner and 'C. J. INVE' in the bottom right corner.

FIG. 5

UNITED STATES PATENT OFFICE.

CARL J. YOUNG, OF SEATTLE, WASHINGTON.

CLAM-SHELL BUCKET.

1,037,570.

Specification of Letters Patent. Patented Sept. 3, 1912.

Application filed September 16, 1911. Serial No. 649,619.

To all whom it may concern:

Be it known that I, CARL J. YOUNG, a citizen of the United States, residing at Seattle, in the county of King and State of Washington, have invented certain new and useful Improvements in Clam-Shell Buckets, of which the following is a specification.

This invention relates to improvements in clam-shell buckets, and has for its object the provision of simple and effective devices for opening and closing the scoop elements of the bucket.

A further object of the invention resides in improved manner of equalizing the stresses imparted to the apparatus in closing the bucket.

A still further object of the invention is the novel means of causing the winding chains that effect the closing of the bucket to wrap spirally about the connected rotatable sleeve.

Other objects of the invention relating to improved construction, ease and certainty of operation will be apparent in the following description.

The invention consists in the novel construction of an excavating bucket of the clam-shell type and particularly in the combination and adaptation of novel closing devices, as will be hereinafter set forth.

In the accompanying drawings, Figure 1 is a side elevation of an embodiment of my invention shown in open condition. Fig. 2 is a similar view of same shown as closed. Fig. 3 is a side elevation of Fig. 2. Fig. 4 is a detached detail view of one of the chain links. Fig. 5 is a diagrammatical cross-sectional view through A—A and B—B of Fig. 1.

Referring to said drawings, the reference numeral 1 designates a pair of bucket-scoops pivotally connected together by the arms 2 to a transverse bar 3. Braces 4 pivotally connected at their upper ends to a rod 5 fixedly secured in a cross-head 6 are pivotally connected at their lower ends to the respective outer corners 7 of the scoops. Rotably mounted on said bar 3 is a sleeve 8 having a centrally disposed sheave 9 fixedly secured thereto and pairs of similarly directed apertured lugs 10, 10' positioned upon each side of said sheave in close proximity upon each side of the latter and adjacent the opposite ends of the sleeve, respectively. The numeral 11 denotes a yoke swingingly connected intermediate its

length to said rod 5 through the strap 12 and pivotally connected intermediate its ends to the latter. At each of its extremities said yoke is provided with a pivotally hung equalizer 13 which are each in turn connected through swivels 15 with a pair of flat linked chains 16. The opposite extremity of each said chain is engaged with one of said pairs of lugs 10 or 10'. A closing cable 17 is run through guide sheave 18 about the sheave 9 to which it is fixedly engaged at 17'. 19 is a hoisting rope fixedly secured to said cross-head.

The link members 20 (see Fig. 4) of a chain are each formed with a slight warp or compound inclination from a normal plane so that when linked in operative condition the chain is in effect twisted as shown in Fig. 1. Said twist is imparted to the chains for the purpose of causing the same to wrap spirally about the sleeve when the latter is rotated and prevent one turn overlying another and interfering with the smooth wrapping of the chain about the sleeve. The equalizers 13 are each positioned over said sleeve about midway between the pairs of lugs 10 and 10' upon each side of the sheave 9. The chains therefore diverge from their connections with the equalizers to their lower connections with said lugs when the bucket is in open condition. An oppositely directed twist is imparted to the chains connected to each equalizer to cause them to wrap spirally about said sleeve in opposite directions toward the adjoining pair of lugs and hang, when fully wound upon the sleeve as shown in Fig. 3, directly under the respective equalizer. The oppositely directed inclination of the upper chain links is illustrated in A—A of Fig. 5 which is a cross-section of the upper links of the chain shown in Fig. 1 and the adjoining chain. B—B of Fig. 5 shows the corresponding relation of the lowermost links in the same view. It should also be explained that as the chains are wrapped spirally about the sleeve in its elevation through the closing of the bucket-scoops the individual links contact squarely with said sleeve and progressively communicate the twist afforded by each to the chain-links thereabove. The movement of the upper links actuates the respective swivel 15 which, by the relative movement of its elements, relieves the chain of its twisting strains. Thus in Fig. 3 the

upper links through B—B are shown as positioned with parallel links as in B—B of Fig. 5.

The operation of the bucket will, it is thought, be obvious from the foregoing description. Assuming that the bucket is closed when the closing cable is slackened, the relatively heavy sheave 9 and its connected parts drop downwardly and thrust the bucket-scoops apart through the agency of the arms 2. In descending, the sheave is rotated by the resistance afforded by the unwinding of the chains 16 and simultaneously winds up in an opposite direction the cable 17 within the peripheral groove of the sheave. In closing the bucket, power is applied through said cable which is of relatively large diameter and exerts sufficient leverage to rotate the sleeve 8 and wind the chains 16 thereon to draw the arms 2 upwardly and thereby close the bucket-scoops together.

It will be evident that through the employment of chains formed in the manner described that the same will with certainty at all times wind upon the sleeve in a spiral condition and thus not interfere or unduly thrust more strain upon one chain than others. That through the agency of the equalizers 13 two chains upon each side of the sheave 9 are employed and the load upon each distributed safely. Similarly, the provision of the yoke 11 further distributes the load as between the chains upon the opposite sides of the sheave and further increases the factor of safety and strength, by due equalization of all strains encountered.

It will be noted that when the bucket is in open condition as shown in Fig. 1, that the chains draw directly from the respective axes of the rod 5 and the bar 3, while

when the bucket is closed and chains are wound about the sleeve 8 and hence are offset from the bar axis. To compensate for such variation in the direction of strain the strap 12 is mounted for limited swinging movements upon said rod 5 and allows of sufficient motion to accommodate the lateral inclination of the chains and effects the direct pull of the chains, equalizers, yoke and connected parts from said bar.

What I claim as my invention, is—

1. In a clam-shell bucket, closing devices for the bucket scoops consisting of a cross-head, a yoke pivotally secured centrally of its length to the cross-head, equalizers pivotally secured to each of the extremities of said yoke, and a pair of chains secured at one end to each of said equalizers and at their other ends to the bar connecting the forward ends of the bucket scoops and formed to wind spirally about said bar.

2. A clam-shell bucket having bucket-scoops with pivotal connections with a bar at their forward ends, a cross-head, and braces pivotally connecting said cross-head and the rear end of said scoops, closing devices for said scoops consisting in a sleeve rotatably mounted on said bar, a sheave fixedly secured to said sleeve, a pair of chains upon each side of said sheave formed to wind in opposite spiral directions upon said sleeve and each fixedly secured at one end to said sleeve and at the other end to said cross-head, devices to equalize the strains between each pair of chains and between the pairs of chains.

CARL J. YOUNG.
